HANGING MEANS FOR AWNINGS AND THE
LIKE

Ben Perlman, New York, N. Y.

Application March 28, 1939, Serial No. 264,517

3 Claims. (Cl. 156—15)

This invention relates to a hanging means for awnings and the like.

The principal object of this invention is to provide a simple, inexpensive and efficient means for hanging awnings.

Another object is to provide such means as will be light in weight, easily adaptable to the various sizes of windows and door openings and may be readily applied to and removed from the awning.

An additional object is to provide such means as will not cause wear to the awning material or cloth but will distribute the hanging strain over a maximum area.

A still further object is to provide a hanging means which will be neat in appearance.

Numerous other objects of this invention will be readily apparent from an examination of the following description taken in conjunction with the accompanying drawing, in which—

Fig. 1 is a perspective view of the device showing the upper hemmed portion of the awning cloth with a rope within the hem and a fragmentary piece of the remainder of the awning cloth;

Fig. 2 is an enlarged sectional view of the device on the line 2—2 of Fig. 1, but also showing by dotted line the hinge-like assembly of the channel members;

Fig. 3 is a fragmentary perspective view of the separated channel members of the device un-assembled and without the awning;

Fig. 4 is a perspective view of the preferred form of operating-pulley hook;

Fig. 5 is a side view of a modified form of operating-pulley hook; and

Fig. 6 is a perspective view of a further modification of the operating-pulley hook.

Referring more particularly to the drawing, A represents, generally, the hanging means, and B, the awning.

The awning may be of any of the customary types. At the upper end of the awning, the canvas, duck or other cloth 10, forming the awning, is folded over a rope or twine 11 and stitched to provide a hemmed upper awning portion with the rope 11 running through the hem longitudinally. This hemmed portion of the awning containing the rope 11 is the part to which the hanging means A is applied.

The hanging means A includes a pair of sheet metal channel members 12 and 13, respectively, substantially the length of the width of the awning. The main portion 14 of the channel member 12 and the main portion 15 of the rear channel member 13 may be of any cross-sectional

shape, so long as when the channel members are assembled together in proper position as herein-after described they provide a substantially tubular member within which the hemmed portion 5 of the awning containing the rope 11 may be carried. In actual practice, for reasons of appearance, efficiency and inexpensive manufacture among other reasons, it has been found that it is advisable to form these main portions 14 and 15, 10 respectively, of the channel members 12 and 13 in a substantially semi-circular cross-sectional shape, to thus form when assembled, a tubular member, substantially circular in cross-section.

Preferably, the front channel member 12 has 15 its main portion 14 formed in an arc slightly greater than a semi-circle and slightly greater than the arc of the main portion 15 of the rear channel member 13. A pair of spaced hanger slots 16 are cut out of the main portion 14 of the 20 front channel member 12 at the upper part thereof adjacent its edge 17 to provide apertures through which the respective hangers 18 (referred to hereinafter) may be passed.

The rear channel member 13 has a pair of 25 spaced hangers 18 preferably integrally formed with the main portion 15 thereof. These hangers 18 project radially upwardly from the upper edge 19 of such main portion 15 and each has an eye 20 for receiving a hook, nail, or other similar 30 securing means (not shown) for fastening the awning assembly to a window frame or building.

Depending substantially radially from the bottom edge 21 of the main portion 15 is a flange 22 extending along the entire length of the main 35 portion 15. This flange 22 is preferably integrally formed with the main portion 15, substantially diametrically opposite to the hangers 18 and having its free edge 23 extending in a substantially opposite direction from the hangers 18.

40 Depending substantially radially from the bottom edge 24 of the main portion 14 is a flange 25 similar to the flange 22, and extending along the entire length of the main portion 14. This flange 25 is also preferably similarly integrally formed 45 with its respective main portion 14, and is substantially diametrically opposite to the hanger slots 16 and has its free edge 26 extending in a direction substantially opposite from the hanger slots 16.

50 The channel members 12 and 13 are intended to be associated in a hinge-like manner by passing the upstanding hangers 18 of the rear channel member 13 through the hanger slots 16 of the front channel member 12, whereby the latter will swing hinge-like on the hangers 18, as

shown in dotted lines in Fig. 1. An aperture 27 is provided at each end of the flange 25 and, where required, additional apertures 28 may be spaced intermediate the end apertures 27. In the flange 22 there are provided apertures 29 which register with the apertures 27 and 28 when the front and rear channel members 12 and 13 are hingedly assembled as described above.

To secure the hanging means A to the awning B, the hingedly-assembled channel members 12 and 13 are parted at their flanges, hinge-like, and the upper hemmed portion of the awning containing the rope 11 is introduced into the tubular portion of the hanging means with the rope 11 extending longitudinally of the channel members. The front and rear channel members 12 and 13 are then brought together so as to form a seat for the hemmed portion of the awning containing the rope 11 and so that the flanges 22 and 25 press therebetween the folds of the awning hem intermediate the rope 11 and the main body of the awning cloth 10. The awning is then drawn downwardly so that the hem at the bottom of the rope 11 will be brought into close seating upon the lower interior portion of the tubular portion of the hanging means A. Holes are then punched in the awning cloth at the points where it extends between the registering apertures 27, 28 and 29, and eyelets, rivets or similar fastenings 30 are then passed through these registering apertures in the flanges and awning cloth and secured in place so that the flanges 22 and 25 grip the awning cloth tightly therebetween.

In actual practice, the upper awning cloth hem has the stitching thereof close to the rope 11, and the short folded-over portion of the upper awning cloth hem which projects beyond the hem stitching is relatively narrower than the flanges 22 and 25 so that the flanges of the assembled hanging means conceal such hem.

The awning cloth at its upper end is thus secured within the hanging means against lateral movement, both by reason of the eyelets 30 which pass through the flanges and awning cloth, and by the gripping action of the flanges extending substantially across the entire awning width. The awning is similarly held against downward movement from the hanging means, and additionally by the seating of the hem at the bottom of the rope 11 upon the lower interior portion of the tubular portion of the hanging means.

Means for attaching operating pulleys for raising and lowering the awning may be provided by a hook 31. Preferably, as shown in Fig. 4, this pulley hook 31 will be cast or bent and formed from a single T-shaped piece of heavy sheet metal, and will comprise a vertical hooked portion 32 with a pair of wings 33 extending horizontally and at right angles to the hooked portion 32. Where bent and formed from a T-shaped piece of sheet metal, the stem of the T will form the hooked portion 32 and the top or cross-piece will form the wings 33 of the pulley hook 31. A restricted aperture 35 is provided in the main portion 15 of the rear channel member 13 intermediate the upper edge 19 and the bottom edge 21 thereof, through which the hooked portion 32 of the pulley hook 31 may be passed from the concave side of the rear channel member 13 with the wings 33 extending longitudinally of the channel member in opposite directions to prevent any but the hooked portion

32 of the pulley hook 31 to pass through such restricted aperture 35.

A modified form of pulley hook such as shown in Fig. 5 may be similarly used. This modified form may be cast or formed of a piece of wire. The hooked portion 32a may be similarly passed through the aperture 35 and a collar 33a projecting from the shank of the pulley hook prevents its passing completely through the restricted aperture 35.

If it is desirable to have the pulley hook rigidly permanently secured to the hanging means, the modified form shown in Fig. 5 or Fig. 6 may be used. Where this is desirable, the end 34a of the pulley hook shown in Fig. 5 is passed from the convex side of the rear channel member 13 until the collar 33a seats against the outer surface of such channel member and the end 34a projects beyond the inner (concave) side thereof, whereupon the end 34a is hammered over rivet-fashion, or bent or otherwise similarly secured, or the further modified form of hook shown in Fig. 6 may be secured by a rivet, eyelet of the like, passing through such hook and main portion 15 of the channel member 13. The hooks may also be secured to the hanging means at the flanges by the eyelets 30 or similar fastening means, or by passing the hook partially through the registering apertures in the flanges.

It will be understood that this invention is not confined to the specific details shown and described as numerous changes and modifications and full use of equivalents may be resorted to without departing from the spirit or scope of the appended claims.

What is claimed is:

1. In an awning assembly, a pair of channel members, hangers on one of said pair of channel members projecting through the other of said pair of channel members whereby to hinge the same together, depending flanges extending along each of said channel members, means for attaching operating pulleys to said hanger-bearing channel member, and means for securing said depending flanges together.

2. An awning hanging means including a pair of sheet metal channel members having the main portion of each thereof substantially semi-circular in cross-section, hangers on one of said pair of channel members projecting through the other of said channel members whereby to hinge the same together at the upper edge thereof to form a substantially circular tubular receptacle for receiving longitudinally therein the thickened upper end of an awning and permitting the main portion of the awning to depend therefrom between the lower edges of said channel members opposite said hinged upper edges, and means for securing said channel members rigidly together to grip said depending portion of the awning between said lower edges of said channel members.

3. An awning hanging means having a separable tubular frame for receiving a thickened upper edge of an awning and forming when closed a seat for said thickened upper edge, said frame having an aperture therethrough, means for attaching an operating pulley to said frame, said means comprising a hook adapted to be passed from within the inner side of said frame through said aperture and means including an enlarged portion on said attaching means for retaining said hook in said frame, and means for maintaining said frame in closed position.

BEN PERLMAN.
